UNITED STATES PATENT OFFICE

103,242

DESIGN FOR A CRAB AND LOBSTER CRACKER

Malcolm W. Lowenstein, Baltimore, Md., assignor
of one-half to Samuel Silberstein, Balti-
more, Md.

Application December 29, 1936, Serial No. 66,784

Term of patent 7 years

To all whom it may concern:

Be it known that I, Malcolm W. Lowenstein, a citizen of the United States, residing in Baltimore, in the State of Maryland, have invented a new, original, and ornamental Design for a Crab and Lobster Cracker, of which the following is a specification, reference being had to the accompanying drawing, forming part thereof.

Fig. 1 is a view in front elevation of a crab and lobster cracker embodying my new design.

Fig. 2 is a view in side elevation of the same.

I claim:

The ornamental design for a crab and lobster cracker, as shown.

MALCOLM W. LOWENSTEIN.
